UNITED STATES PATENT OFFICE.

ALBEN E. LUNDELL, OF CHICAGO, ILLINOIS, AND JAMES J. WYNNE, OF ROSELLE PARK, NEW JERSEY, ASSIGNORS TO WESTERN ELECTRIC COMPANY, INCORPORATED, OF NEW YORK, N. Y., A CORPORATION OF NEW YORK.

TELEPHONE-EXCHANGE SYSTEM.

Application filed July 1, 1920. Serial No. 393,377.

To all whom it may concern:

Be it known that we, ALBEN E. LUNDELL and JAMES J. WYNNE, citizens of the United States, residing at Chicago, in the county 5 of Cook and State of Illinois, and at Roselle Park, in the county of Union and State of New Jersey, respectively, have invented certain new and useful Improvements in Telephone-Exchange Systems, of which the following is a full, clear, concise, and correct 10 description.

This invention relates to automatic telephone exchange systems and more particularly to systems employing switches of the power driven type and in which the switches 15 are controlled by means of a sender located at the central office.

It is the object of this invention to provide an intermediate registering device of 20 such a nature that a change of routing may be made by simply altering the connections at a common cross connecting board instead of being obliged to alter the wiring of each 25 sender involved.

It is a further object of the invention to provide suitable mechanism and circuits for 30 accomplishing the transfer of registrations from one set of registers to another in a novel manner.

An additional object of the invention is 35 the provision of a quick acting registering device which may be positioned under the joint control of a plurality of primary registering devices. In the present disclosure 40 the primary registering devices have been shown as operator controlled keys, but it is to be understood that such keys show merely one embodiment of the invention and that other forms of primary registering devices 45 such as registers positioned under the control of an impulse transmitter may be utilized without departing from the spirit of the invention.

A feature of the invention is the use of a 50 multi-position switch which is positioned in accordance with the settings of a plurality of registering devices.

A further feature of the invention resides 55 in the provision of means for actuating a set of register relays under the control of an impulse sending device in accordance 60 with the setting of the aforesaid multiposi-

tion switch. The impulse sending device is preferably common to all the register relays 55 of the exchange.

Other features of the invention result from the arrangement of the controlling circuits for said switch and register relays, and will be clearly apparent from the detailed description which follows. 60

The invention has been shown applied to a semi-mechanical system of the type shown in Patent No. 1,345,016, issued June 29, 1920, to A. E. Lundell and F. A. Stearn. The invention is, however, obviously capable 65 of a wide range of usage and is therefore to be limited only by the appended claims.

In the drawing the various figures show so much of a telephone exchange system as is necessary to an understanding of the invention. Fig. 1 shows a link circuit at a cordless operator's position and includes a district selector switch and controlling circuits therefor. Fig. 2 shows a link circuit to be used in associating an idle sender with the cord circuit which has been taken for use and includes the controlling circuits for a cord finder switch and a sender selector switch. Fig. 3 shows a portion of the control circuit for setting the sender register 70 relays. Fig. 4 shows a set of counting relays for controlling the operation of the various selector switches of the system together with a sequence switch to control the progress of operations in the sender. first be given in order that the detailed description which follows may be more readily understood.

The general operation of the system is substantially similar to that described in the above mentioned Patent to A. E. Lundell and F. A. Stearn, No. 1,345,016. The operator controlling the district switch shown in Fig. 1 assigns the trunk shown in such figure, after receiving instructions from an A operator (not shown) over an order wire (not shown). The A operator then plugs into such trunk causing the operation of signals which inform the cordless operator, as she will be termed hereafter, that a call is awaiting extension. The cordless operator then depresses an assignment key, whereupon the link circuit shown in Fig. 2 is put into operation. In practice there would be a number of these link circuits under the control of an allotter, but for the sake of simplicity only one link circuit has been shown. The link circuit is provided at each end with a hunting switch. The cord finder at one end hunts for the district circuit at which the assignment key has been depressed, while the sender selector on the other end of such link, hunts for an idle sender. The cordless operator is provided with a set of office keys and with a set of numerical keys. The numerical keys correspond to those described in the above mentioned application and are not shown in the present application in order to avoid needless complication. The operator's office key set comprises two rows of keys, there being one set of vertical keys and another set of horizontal keys. Assuming that there are ten horizontal keys and twenty vertical keys it is obvious that by using these keys on a coordinate basis two hundred combinations may be obtained. The arrangement of these keys on the key board is shown and described in Patent No. 1,369,003, issued February 22, 1921, to W. G. Blauvelt.

After the operator has depressed the assignment key she will depress the proper office keys and the proper numerical keys. The multiposition switch shown in Fig. 6, which will hereafter be termed a translator switch, is then put into operation to assume a position determined by the particular office key depressed in both the horizontal and the vertical row. During the hunting movement of the translator switch, the registration set up on the numerical keys is transferred to the sender register relays (not shown) in a manner substantially the same as in the aforementioned Lundell-Stearns patent.

After the translator switch has been positioned, an impulse generating machine comprising a plurality of drums which may be variably wired to the terminals engaged by the translator switch brushes, operates to

energize the register relays of Fig. 7 in variable combinations. The impulse generating machine is preferably connected to the terminals of the translator switch by means of a distributing frame so that changes in routing may be conveniently accomplished. The translator switch may then be restored and the registration is then transferred from the relays shown in Fig. 7 to the sender register relays of Fig. 5.

After the registration has been set up on the relays of Fig. 5 the operation of the system is substantially similar to that described in the previously mentioned Patent No. 1,345,016 to A. E. Lundell and F. A. Stearn.

The drums on the impulse generating machine or impulser, as it may be termed, are mounted on the same shaft and are in continuous rotation. In order that a better understanding of the sequence of events during a rotation of the impulser may be had the drums have been developed into a plane surface, the rectangles and squares on this surface representing points at which grounded battery is supplied to any brush which is in engagement with such segment. The direction of rotation of the drums is assumed to be in the direction of the arrow as shown in Fig. 6.

The advantage arising from the use of the translator switch is readily apparent even from the above general description. It is obvious that each of the translator switches may be made to serve a portion of a multiple contact bank, which may be of the well-known type ordinarily used in connection with the type of switch chosen for use as a translator which will be described hereinafter. Therefore, any time that it is desirable to change the routing of a call, the only connections which must be changed are those extending from one set of multiple terminals to the brushes of the impulser, and the proper change will then be automatically transferred to the sender register relays at the proper time.

It is, of course, obvious that the translator switches used by the various operators in the exchange may all have access to a multiplied portion of the contact bank.

If a number of sections of multiple contact banks are used, the terminals of such banks are brought to a distributing frame so that in order to change the connection from the impulser to any contact, it is necessary to change only one connection.

The mechanical structure of the translator switch is immaterial to the inventive idea. In the present embodiment of the invention the translator switch used is substantially similar to a switch described in Patent No. 1,123,696 issued to E. B. Craft and J. N. Reynolds on January 5, 1915. In the present case it has been assumed that each of the multiple brush sets comprises a set of six

brushes. All of these brush sets are normally inoperative as is usual in a panel-type power driven selector switch and any one may be selected in the usual manner and 5 rendered operative upon actuation of a trip rod which serves to release the six brushes comprising the selected brush set into physical engagement with a section of the contact bank served by them. Each brush set is 10 arranged to travel over a section of the bank comprising forty terminals. A controlling commutator and associated commutator brushes are provided, this commutator being provided with segments suitably disposed to accomplish the control of the switch 15 in accordance with the principles of the invention.

A detailed description of the operation of the system will now be given. 20 It will be assumed that a subscriber at an outlying manual office wishes to originate a call. For the purpose of simplifying the description and drawings, it has been assumed that this call is to be extended to 25 a desk located in the office containing the operator's equipment. This means that no office selectors need be employed since the call is local and there will be no utility for numerical designation. The numerical keys 30 and registers and their controlling circuits have therefore been omitted.

When the calling subscriber removes his receiver from the switchhook, he will cause 35 a signal to be lighted before an "A" operator's position (not shown). The "A" operator will respond to this signal by plugging into the answering jack of the calling subscriber's line and will then converse with him to ascertain the office and numerical 40 designation of the call. The "A" operator will then converse with the cordless operator, one of whose circuits is shown in Fig. 1, by means of an order wire. The cordless operator will then assign a trunk and the 45 "A" operator will plug into the outgoing end of such trunk. The substation of the calling subscriber and the "A" operator's cord circuit together with the outgoing end of the trunk have not been disclosed. Suitable 50 circuits for this purpose are, however, shown in Patent No. 1,342,823, issued June 8, 1925, A. E. Lundell and E. H. Clark.

As soon as the "A" operator has plugged 55 into the trunk terminating in Fig. 1 in conductors 101 and 102, a circuit is completed from grounded battery, sequence switch contact 103, right-hand winding of relay 104, conductor 101, through the cord circuit of the "A" operator and a supervisory relay included therein, returning by 60 way of conductor 102, left-hand winding of relay 104, sequence switch contact 105 to ground. Relay 104 is energized in this circuit and completes a circuit from ground- 65 ed battery, left-hand winding of relay 106,

sequence switch contact 107, armature and contact of relay 104 to ground. Relay 106 is energized in this circuit and completes a circuit from grounded battery through lamp 108, left-hand contacts of sequence 70 switch spring 109, inner right-hand armature and front contact of relay 106, right-hand contact of sequence switch spring 110, outer right-hand armature and front contact of relay 106, lower contacts of sequence 75 switch spring 111 to ground. The lamp 108 is lighted to inform the cordless operator that the "A" operator has plugged into the trunk jack. She thereupon depresses a non-locking assignment key 112, thereby completing a circuit from grounded battery, power magnet of sequence switch 100, lower contact of sequence switch spring 113, left-hand contacts of key 112, to ground, for moving this sequence switch out of position 80 1 and into position 2. As soon as sequence switch 100 leaves position 1, the circuit of relay 106 is broken and this relay deenergizes.

In position 2 of sequence switch 100, a 90 circuit is completed from grounded battery, winding of relay 201, (Fig. 2), left-hand contacts of sequence switch spring 202, conductor 203, upper left-hand and lower right-hand contacts of sequence switch spring 95 114, inner right-hand armature and back contact of relay 106, upper contacts of sequence switch spring 109 to ground. Relay 201 is energized in this circuit and completes a circuit from grounded battery, left-hand winding of relay 204, upper contacts of sequence switch spring 205, outer right-hand armature and front contact of relay 201 to ground. Relay 204 is energized in this circuit and completes a circuit from 100 105 grounded battery, power magnet of sequence switch 200, upper right-hand contact of sequence switch spring 206, inner right-hand armature and front contact of relay 204, to ground, for moving this sequence switch out of position 1 and into 110 position 2.

In position 2 of sequence switch 200, a circuit is completed from grounded battery, winding of up-drive magnet 207, left-hand 115 contacts of sequence switch spring 205, outer right-hand armature and front contact of relay 201 to ground. Under the control of magnet 207, the cord finder brush shaft is elevated in search of the terminal set corresponding to the district switch circuit at 120 which the associated assignment key has been depressed. It is to be noted that as soon as sequence switch 200 leaves position 1½, relay 201 is maintained energized over 125 a circuit extending through the lower contacts of sequence switch spring 202, the left-hand armature and back contact of relay 208, the upper right-hand and lower left-hand contacts of sequence switch spring 209 130

to ground. The test terminals associated with district switch circuits, whose controlling sequence switches are in any other position than position 2, are characterized by the absence of ground. Therefore test relay 208 does not become energized until the cord finder test brush 210 engages test terminal 211, whereupon a circuit is completed from grounded battery, winding of relay 208, upper contact of sequence switch spring 212, test brush 210, test terminal 211, conductor 213, upper contacts of sequence switch spring 215, outer right-hand armature and back contact of relay 106, lower contacts of sequence switch spring 211 to ground. Relay 208 is energized and at its left-hand armature opens the circuit of relay 201. Relay 201 remains energized for an instant longer due to a locking circuit extending from its inner right-hand armature and front contact, commutator 214, commutator brush 215 to ground. When, an instant later, commutator brush 215 engages an insulating segment of commutator 214, at which time the cord finder brush set will be correctly centered on the selected terminal set, relay 201 is deenergized and opens at its outer right-hand armature the driving circuit of magnet 207, which deenergizes and allows the cord finder to come to rest. The deenergization of relay 201 completes a circuit from grounded battery, power magnet of sequence switch 200, lower left-hand contact of sequence switch spring 206, outer right-hand armature and back contact of relay 201 to ground, for moving this sequence switch out of position 2 and into position 3.

The operation of the sender selector shown at the right of Fig. 2 is simultaneous with the operation of the cord finder. It will be recalled that relay 204 was energized upon the initial energization of relay 201 to cause the advance of sequence switch 200 into position 2. When sequence switch 200 leaves position 1 $\frac{1}{2}$, the energizing circuit of relay 204 is interrupted at the right-hand contact of sequence switch spring 205, but if at this time the first sender is busy, which will be indicated by the fact that its controlling sequence switch 300 is in some position other than 1, a locking circuit is completed through the left-hand winding of relay 204, left-hand armature and front contact of relay 204, left-hand contacts of sequence switch spring 216, sender selector brush 217, which is engaging test terminal 218 of the set of terminals associated with the first sender, conductor 219, right-hand winding of relay 301, upper left-hand and lower right-hand contacts of sequence switch spring 302 to ground. With sequence switch 200 in position 2, a circuit is completed from grounded battery, winding of up-drive magnet 220 of the sender selector, contacts of sequence switch spring 221, inner right-hand armature and front contact of relay 204 to ground. Magnet 220 is energized in this circuit and causes the sender selector brush shaft to be moved upward in search of an idle sender. As soon as test brush 217 engages a test terminal 218 on which there is no ground potential, the locking circuit of relay 204 is broken. Relay 204 is maintained energized a moment longer, however, due to the existence of a circuit extending from grounded battery, right-hand winding of relay 204, lower left-hand and upper right-hand contacts of sequence switch spring 222, conducting segment of commutator 223, commutator brush 224 to ground. When, a moment later, brush 224 engages an insulating segment of commutator 223, at which time the sender selector brush set will be accurately centered on the terminal set of an idle sender, the circuit through the right-hand winding of relay 204 is broken and this relay deenergizes, causing in turn the deenergization of up-drive magnet 220, thus bringing the sender selector to rest. It is to be observed that if the sender selector is the first to complete its operation the sequence switch 200 will remain in position 2 until the cord finder has completed its operation, whereupon it will be moved into position 3. The deenergization of relay 204 then completes a circuit from grounded battery, power magnet of sequence switch 200, lower right-hand contact of sequence switch spring 206, inner right-hand armature and back contact of relay 204 to ground, for moving this sequence switch out of position 3 and into position 4.

If the cord finder is the first to complete its operation, the sequence switch 200 will be advanced out of position 2 and into position 3 as previously described. In position 3, the operation of the sender selector will continue as above described, since the circuits therein traced in each case function to the same purpose whether the sequence switch is in position 2 or position 3 as may be readily ascertained by inspection of the drawing.

As soon as the sender circuit shown in Figs. 3, 4 and 5 has been seized and the sequence switch 200 has reached position 4, a circuit is completed from grounded battery, left-hand winding of relay 301 (Fig. 3), upper right-hand and lower left-hand contacts of sequence switch spring 303, conductor 304, terminal 225, brush 226, right-hand contacts of sequence switch spring 227, to ground. Relay 301 is energized in this circuit and locks up through its left-hand armature and front contact to conductor 219 which is grounded by way of the upper left-hand and lower right-hand contacts of sequence switch spring 216. Ground potential is also supplied to test terminal 218 to render this sender non-selectable to other hunting send-

er selectors. Relay 301 upon energization also completes a circuit from grounded battery, power magnet of sequence switch 300, lower left-hand contact of sequence switch spring 305, left-hand armature and front contact of relay 301 to ground for moving this sequence switch out of position 1 and into position 6.

With sequence switch 200 in position 4 and sequence switch 100 in position 2, a circuit is completed from grounded battery, right-hand winding of relay 204, left-hand contacts of sequence switch spring 222, inner right-hand armature and front contact of relay 228, which was energized when test relay 208 operated incident to the finding of the desired cord, cord finder brush 229, terminal 230, conductor 231, lower contact of sequence switch spring 116 to ground. Relay 204 is energized in this circuit and completes a circuit from grounded battery, power magnet of sequence switch 200, upper right-hand contact of sequence switch spring 206, inner right-hand armature and front contact of relay 204, to ground for moving this sequence switch out of position 4 and into position 5.

As soon as sequence switch 200 reaches position 5, a circuit is completed from grounded battery, power magnet of sequence switch 100, conductor 117, lower contacts of sequence switch spring 118, conductors 119 and 120, terminal 232, brush 233, outer left-hand armature and front contact of relay 228, upper contact of sequence switch spring 234, to ground, for moving sequence switch 100 out of position 2 and into position 3.

As soon as sequence switch 100 leaves position 2, the energizing circuit of relay 204 is broken and this relay deenergizes and completes a circuit from grounded battery, power magnet of sequence switch 200, lower right-hand contact of sequence switch spring 206, inner right-hand armature and back contact of relay 204 to ground for moving this sequence switch out of position 5 and into position 6.

As soon as sequence switch 100 reaches position 3, a circuit is completed from grounded battery, left-hand winding of relay 106, lower right-hand contact of sequence switch spring 121, conductor 122, lower contact of sequence switch spring 123, to ground. Relay 106 is energized and completes a circuit from grounded battery, power magnet of sequence switch 100, conductor 117, left-hand contacts of sequence switch spring 124, inner right-hand armature and front contact of relay 106, upper contacts of sequence switch spring 109 to ground for moving this sequence switch out of position 3 and into position 5. As soon as sequence switch 100 leaves position 3 the energizing circuit of relay 106 is broken and

this relay deenergizes. The district sequence switch remains in position 5 until the fundamental circuit for controlling the selective operation of the switch is completed.

The operation of setting up the wanted number on the various registers will now be described. As previously mentioned, the operator is provided with a set of keys to control office selection comprising a row of 75 horizontal keys indicated generally at H in Fig. 6 and numbered from 1 to 10 and a row of twenty vertical keys shown generally at V, Fig. 6, and numbered from 1 to 20. She is also provided with a keyset provided with ten keys for each digit in the wanted number, these ten keys representing respectively the ordinals from 0 to 9. The numerical keys and the method in which they function to control registers has not been 85 described.

The incoming call is to be diverted to the attention of an operator at a local desk. Assuming that the office code corresponding to a call which is to be routed to a local desk is AX, the cordless operator will immediately after depressing assignment key 112, as previously described, depress key No. 7 in the H row and key No. 15 in the V row.

As soon as key A is depressed, a circuit is completed from grounded battery, winding of relay 701, Fig. 7, upper contact of sequence switch spring 702, conductors 703 and 704, right-hand contacts of key A, conductor 600 to ground. Relay 701 is energized in this circuit and completes a circuit from grounded battery, power magnet of sequence switch 700, conductors 705 and 706, upper right-hand contact of sequence switch spring 707, right-hand armature and front contact of relay 701 to ground for moving this sequence switch out of position 1 and into position 2. As soon as sequence switch 700 reaches position 1 $\frac{1}{4}$, relay 701 completes a locking circuit for itself through its right-hand armature and front contact and the left-hand armature and back contact of relay 708 to ground by way of the upper left-hand contact of sequence switch spring 709.

In position 2 of sequence switch 700, brush selection is accomplished by the translator switch shown in Fig. 6. The circuit of up-drive magnet 601 extends from grounded battery, winding of magnet 601, conductor 602, upper left-hand and lower right-hand contacts of sequence switch spring 710, left-hand armature and front contact of relay 701 to ground. It is to be observed that with sequence switch 700 in position 2, relay 603, Fig. 6, is energized over a circuit extending from grounded battery, winding of relay 603, conductor 604, right-hand contact of sequence switch spring 711 to ground.

During the upward movement of the 130

translator brush shaft, commutator test brush 605 successively engages the commutator segments in the right-hand group of the main commutator plate 606. The first 5 five contacts to be engaged by brush 605 are utilized to determine which set of brushes shall be selected. Each brush set serves a group of forty terminal sets. These forty terminal sets are arranged in a continuous 10 group. A novel controlling circuit has been introduced, the operation of which will be subsequently described, so that in case the desired terminal set is in the lower twenty, the selected brush set will begin hunting 15 starting from the lowermost terminal in the lower twenty. In case, however, the desired terminal set is in the upper twenty, the selected brush set will be moved over the contacts of the lower twenty without hunting in 20 such group and will come to rest with its brushes in engagement with the lowermost terminal set in the upper twenty. Thereafter it will be caused to hunt for the proper terminal set. From this it is obvious that 25 the selection of the desired one of two hundred terminal sets is accomplished, first, by selecting one of five brushes to select a group of forty terminals. Selection is then made to select an upper or lower group of twenty 30 terminals, after which the desired terminal is selected. The selection of a brush set and the selection of a twenty group is made under the control of a key in the horizontal column. The selection of the particular contact 35 in the twenty group is always under the control of a key in the vertical column.

The translator brush shaft is moved upwardly as described until commutator brush 605 engages commutator segment 607, at 40 which time a circuit is completed from grounded battery, winding of relay 708, right-hand contact of sequence switch spring 712, conductor 713, brush 605, segment 607, armature 608 and its front contact, conductors 609 and 610, closed left-hand contacts of key A, conductor 611, lower right-hand contact of sequence switch spring 709 to ground. Relay 708 is energized in this circuit and locks up to ground through its 45 right-hand armature and the upper right-hand contact of sequence switch spring 709. Relay 708 at its left-hand armature opens the locking circuit of relay 701. Relay 701 is maintained energized a moment longer, 50 however, due to the existence of a circuit extending by way of conductor 714, a conducting segment of commutator 612, commutator brush 613 to ground. When, a moment later, commutator brush 613 engages 55 an insulating segment of commutator 612, at which time the selected brush set will be accurately positioned for brush tripping, relay 701 is deenergized and at its left-hand armature opens the circuit of up-drive mag- 60 net 601, causing the translator brush shaft 65

to be brought to rest. The deenergization of relay 701 also completes a circuit from grounded battery, power magnet of sequence switch 700, conductors 705 and 706, lower right-hand contact 707 and back contact of relay 701 to ground, for moving this sequence switch out of position 2 and into position 3.

In position 3 of sequence switch 700, a circuit is completed from grounded battery, 75 winding of trip magnet 614, conductor 615, left-hand contact of sequence switch 711 to ground. Trip magnet 614 is energized and operates the trip rod controlled by it so that upon the subsequent upward movement of 80 the translator switch the second set of brushes will be released into operative relation with the group of terminals served by it.

The keys numbered from 1-5 inclusive in the horizontal row are arranged to cause a 85 selected brush set to hunt for a particular one of twenty terminals in the lower twenty of a selected group of forty terminals. This is accomplished due to the fact that ground is supplied to conductor 720 by way of the 90 right-hand contacts of such keys when actuated. Any one of keys 6 to 10 in the horizontal row when actuated determine that hunting for the desired terminal set shall take place after the lower twenty group has 95 been traversed. This is accomplished by supplying ground to conductor 704 by way of the right-hand contacts of such keys. The manner in which the discrimination between twenty groups is accomplished will 100 now be described.

Since key A has been depressed, which is one of the keys numbered 6 to 10 in the horizontal group, the desired terminal set is located in the upper twenty. Therefore, 105 with sequence switch 700 in position 3, a circuit is completed from grounded battery, winding of relay 701, upper right-hand contact of sequence switch spring 702, conductors 703 and 704, closed right-hand contact 110 of key A, conductor 600 to ground. Relay 701 is energized in this circuit and locks up through its right-hand armature and front contact and the left-hand armature and back contact of relay 708, which was deenergized 115 when sequence switch 700 left position 2, to ground by way of sequence switch spring 709. Relay 701 at its left-hand armature completes a circuit from grounded battery, power magnet of sequence switch 700, upper 120 right-hand contact of sequence switch spring 707, left-hand armature and front contact of relay 701 to ground for moving this sequence switch out of position 3 and into position 4.

In position 4 of sequence switch 700, a 125 circuit is completed from grounded battery, winding of up-drive magnet 601, conductor 602, upper left-hand and lower right-hand contacts of sequence switch spring 710, left-hand armature and front contact of relay 701 130

to ground. No test of the terminals in the lower twenty is made as commutator brush 605 passes over the commutator segments corresponding to such terminal sets. However, as soon as test brush 605 engages the commutator segment corresponding to the lowermost terminal set in the upper group of twenty, which is segment 618, a circuit is completed from grounded battery, winding 10 of relay 708, right-hand contacts of sequence switch spring 712, conductor 713, brush 605, terminal 618, conductor 619, lower left-hand contact of sequence switch spring 715, conductor 704, closed right-hand contacts of 15 the A key, conductor 600 to ground. Relay 708 is energized in this circuit and at its left-hand armature opens the locking circuit of relay 701. Relay 701 remains energized as 20 previously described until the brush set is accurately centered, whereupon it deenergizes and completes a circuit from grounded battery, power magnet of sequence switch 700, conductors 705 and 706, lower right-hand contact of sequence switch spring 707, left- 25 hand armature and back contact of relay 701, to ground, for moving this sequence switch out of position 4 and into position 5. Relay 708 is deenergized as soon as sequence switch 700 leaves position 4.

30 As soon as sequence switch 700 reaches position 5, a circuit is completed from grounded battery, winding of relay 701, conductor 716, contacts of sequence switch spring 717, conductor 718, closed right-hand contact of 35 key X, conductor 619 to ground. Relay 701 is energized and completes a circuit for moving sequence switch 700 out of position 5 and into position 6, identical with the circuit traced for moving it from position 3 to 40 position 4. Relay 701 upon energization locks up through the left-hand armature and back contact of relay 708 as previously described.

In position 6 of sequence switch 700, the 45 translator switch is moved upwardly in its final hunting movement, the circuit of up-drive magnet 601 extending to ground at the left-hand armature and front contact of relay 701 over a path previously described.

50 When test brush 605 engages commutator segment 620, which is the segment in the upper twenty, associated with key X, a circuit is completed from grounded battery, winding of relay 708, contacts of sequence 55 switch spring 712, conductor 713, brush 605, segment 620, conductor 621, closed left-hand contact of key X, conductor 622, upper right-hand contact of sequence switch spring 719 to ground. Relay 708 is energized in 60 this circuit and opens at its left-hand armature the locking circuit of relay 701. When, a moment later, commutator brush 613 engages an insulating segment of commutator 65 612, relay 701 deenergizes and opens the circuit of up-drive magnet 601, allowing the

translator brush shaft to come to rest with the second set of brushes in engagement with the thirty-fifth terminal set in the group served by it. Relay 701, upon deenergization, also completes a circuit from grounded 70 battery, power magnet of sequence switch 700, conductors 705 and 706, lower right-hand contact of sequence switch spring 707, left-hand armature and back contact of relay 701 to ground for moving this sequence 75 switch out of position 6 and into position 7.

In order that the setting operation of the translator switch may be more fully understood, its operation when a terminal set in the lower twenty is to be selected will be 80 briefly described. It will be assumed that key E in the horizontal row has been depressed and that key X in the vertical row has been depressed. In this case, when sequence switch 700 reaches position 2, the 85 translator switch is moved into position to select the second set of brushes in a manner identical with that previously described, and sequence switch 700 is then moved into position 3. No circuit is found for relay 90 701 in position 3 of sequence switch 700 under the assumptions that have now been made. Sequence switch 700 is, however, immediately moved out of position 3 by means 95 of a circuit extending from grounded battery, power magnet of sequence switch 700, conductors 705 and 706, upper left-hand contact of sequence switch spring 707, conductor 720, closed right-hand contacts of key E 100 to ground. As soon as sequence switch 700 reaches position 4, it is immediately moved out of position 4 and into position 5 by means of a circuit extending from ground battery, power magnet of sequence switch 700, conductors 705 and 706, lower right-hand contact of sequence switch spring 707, left-hand armature and back contact of relay 701 to ground. Sequence switch 700 is 105 then moved out of position 5 and into position 6 by means of circuits previously described. In position 6, up-drive magnet 601 is again energized and the translator brush shaft is moved upwardly. When commutator brush 605 engages commutator segment 623, a circuit is completed from grounded 110 battery, winding of relay 708, contacts of sequence switch spring 712, conductor 713, brush 605, terminal 623, conductors 624 and 621, closed left-hand contacts of key X and thence to ground as previously described. In 115 this case the translator brush is brought to rest with its selected brush set in engagement with the fifteenth contact set in the group of terminals served by it.

As soon as the translator switch is positioned the first transfer of the office registration has been accomplished since the position assumed by such translator switch determines what district and office selections are to be made. The method of transferring 125 130

this registration from the translator switch to the register relays shown in Fig. 7 by means of the impulse sending device indicated generally at 625 will now be described.

5 The impulser as shown in Fig. 6 is provided with eleven sending drums and associated brushes and with four receiving drums and associated brushes. The sending drum brushes have been numbered from 626 to 636 inclusive while the receiving drum brushes have been numbered from 637 to 640 inclusive. It is obvious that the terminals in the translator switch bank may be 10 variably wired to the sending brushes in any desired combination to control the registration of the various designations necessary to control office selection. The distributing frame whereby such variable wiring may, readily be accomplished is indicated 15 generally at 690 in the drawing.

10 Referring now to Fig. 7, it is to be noted that with sequence switch 700 in position 7, a circuit is completed from grounded battery, winding of relay 721, upper left-hand contact of sequence switch spring 722 to ground. Relay 721 is energized in this circuit.

Assuming that the position of the brushes with respect to the conducting segments on the impulser 625 at the instant sequence switch 700 reaches position 7 is that shown in Fig. 6, the operation of the register relays of Fig. 7 is as follows, it being remembered that the segments included within the rectangle at 625 are connected to grounded battery. The impulser will rotate until brushes 626, 627, 631 and 632 make contact with segments 641, 642, 643 and 644 respectively. As a result of these contacts, the following circuits are completed: grounded battery, segment 643, brush 631, terminal 645, brush 646, conductor 647, armature 723, winding of relay 724 to ground: grounded battery, segment 642, brush 627, terminal 648, brush 649, conductor 650, armature 725, winding of relay 726 to ground: grounded battery, segment 644, brush 632, terminal 651, brush 653, conductor 654, armature 727, winding of relay 728 to ground. Relays 724, 726 and 728 are energized as a result of the completion of these circuits and complete obviously traced energizing circuits for relays 729, 730 and 731.

When brush 638 engages segment 655, circuits are completed for relays 732, 733 and 734 respectively. The circuit of relay 732 extends from ground, left-hand winding of relay 732, armature 735 of relay 731, conductor 736, brush 638, segment 655 to grounded battery. The circuit of relay 733 extends from ground, left-hand winding of relay 733, armature 737 of relay 730, conductor 736 and thence to grounded battery as described. The circuit of relay 734 extends from ground, 65 left-hand winding of relay 734, armature 738

of relay 729 and thence to grounded battery. Relay 732 upon energization locks up through its right-hand winding and right-hand armature and front contact to conductor 739 which is grounded at the lower right-hand contact of sequence switch spring 719. Relay 733 completes a similar locking circuit to grounded conductor 740 and relay 734 completes a locking circuit to grounded conductor 739. As soon as the sending brushes 626, etc. leave their associated segments, relays 726, 728 and 724 deenergize causing in turn the deenergization of relays 729, 730 and 731.

The impulser continues to rotate and when the second vertical row of segments comes into engagement with the brushes served by them, another set of circuits is completed. These circuits are as follows: grounded battery, segment 656, brush 627, terminal 648, brush 649, conductor 650, armature 725, winding of relay 726 to ground: grounded battery, segment 658, brush 632, terminal 651, brush 653, conductor 654, armature 727, winding of relay 728 to ground: grounded battery, segment 659, brush 634, terminal 660, brush 661, conductor 662, armature 741, winding of relay 742 to ground. Relays 726, 728 and 742 are energized and complete energizing circuits for relays 729, 730 and 749 respectively. As soon as brush 639 engages conducting segment 663, which is the next receiving drum segment, circuits are completed for relays 743, 744 and 745. The circuit of relay 743 extends from ground, left-hand winding of relay 743, armature 746 of relay 729, conductor 747, brush 639, segment 663 to grounded battery. The circuit of relay 744 extends from ground, left-hand winding of relay 744, armature 748 of relay 749, which was energized when relay 742 was energized, conductor 747 to grounded battery. The circuit of relay 745 extends from ground, left-hand winding of relay 745, armature 750 of relay 730, conductor 747 to grounded battery. As soon as brush 639 leaves segment 663 the energizing circuits of relays 743, 744 and 745 are broken but these relays are maintained energized due to the completion of locking circuits through their right-hand windings. As soon as the commutator brushes leave the second vertical row of segments, relays 726, 742 and 728 are deenergized causing in turn the deenergization of relays 729, 749 and 730.

As soon as the third vertical row of segments of the impulser come into contact with the impulser brushes the following circuits are completed: grounded battery, segment 664, brush 631, terminal 645, brush 646, conductor 647, armature 723, winding of relay 724 to ground: grounded battery, segment 665, brush 632, terminal 651, brush 653, conductor 654, armature 727, winding of relay 728 to ground: grounded battery, segment 130

666, brush 634, terminal 660, brush 661, conductor 662, armature 741, winding of relay 742 to ground: grounded battery, segment 667, brush 635, terminal 672, brush 673, conductor 674, armature 751, winding of relay 752 to ground: in parallel with the last circuit, from grounded battery, segment 667, brush 635, terminal 669, brush 670, conductor 671, armature 754, relay 755 to ground. Relays 752, 742, 728, 724 and 755 are energized as a result of the completion of these circuits, causing in turn the energization of relays 753, 749, 730, 731 and 756. When receiving brush 640 engages segment 668, circuits are completed for energizing relays 757, 758, 759, 760 and 761. The circuit of relay 757 extends from ground, left-hand winding of relay 757, armature 762 of relay 753, conductor 763, brush 640, segment 668 to grounded battery. The circuit of relay 758 extends from ground, left-hand winding of relay 758, armature 764, conductor 763 to grounded battery. The circuits of relays 759, 760 and 761 are obviously traceable in view of the previous description. When segment 668 leaves brush 640, the energizing circuits over the left-hand windings of relays 757 to 761 inclusive are broken, but these relays remain locked up through their right-hand windings. As soon as the third vertical row of segments passes from engagement with their associated brushes, relays 752, 742, 728, 724 and 755 are deenergized causing in turn the deenergization of relays 753, 729, 749, 730, 731 and 756.

When the fourth vertical row of segments engages the associated brushes, the following circuits are completed: from grounded battery, segment 674, brush 634, terminal 660, brush 661, conductor 662, armature 741, winding of relay 742 to ground: from grounded battery, segment 675, brush 635, terminal 672, brush 673, conductor 674, armature 751, winding of relay 752 to ground: in parallel with the last traced circuit, from grounded battery, segment 675, brush 635, terminal 669, brush 670, conductor 671, armature 754, winding of relay 755 to ground. Relays 752, 742 and 755 are energized as a result of the completion of these circuits causing in turn the energization of relays 753, 749 and 756.

When segment 676 engages brush 637, energizing circuits are completed for relays 764, 765 and 766. The circuit of relay 764 extends from ground, left-hand winding of relay 764, innermost armature of relay 753, conductor 767, brush 637, segment 676 to grounded battery. The circuits of relays 765 and 766 are readily traced in view of the previous description. When segment 676 passes from engagement with its associated brush 637, the energizing circuits of relays 764, 765 and 766 are broken, but these relays remain energized due to the

closure of locking circuits through their right-hand windings and right-hand armatures and front contacts. When segments 674 and 675 pass out from under their associated brushes, relays 752, 742 and 755 are deenergized causing in turn the deenergization of relays 753, 749 and 756. All of the register relays of Fig. 7 which must be actuated to receive the full registration have now been energized. It is therefore obvious that a single revolution of the impulser 625 serves to control the complete registration.

It is to be observed that only one impulser is needed to serve the entire exchange. The brushes of the impulser may be wired to the contacts in the terminal bank as required and may be multiplied whenever necessary without danger of interference between the various translator switches, since the relays of the register set shown in Fig. 7 are affected only by the position of the particular translator switch associated with them.

Consideration of the register relays of Fig. 7 will show that they are twenty-four in number, divided into six lateral rows of four relays each. The first lateral row of relays is used to control peg count, the second row controls class registration, the third row controls district brush registration, the fourth row controls district group registration, the fifth row controls office brush registration and the sixth row controls office group registration. There is a corresponding brush on the translator for each row of relays, or each separate register as they may be considered to be.

There are as many impulse receiving stages as there are relays in each register, that is, since there are four relays in each register, it follows that there are four impulse receiving stages. During the first impulse receiving stage (which was described last in the description just given in view of the position in which the impulser was assumed to be at the start of operations) the No. 1 relays in each register are actuated provided that the brushes corresponding to such registers are connected to brushes which at that instant are making contact to grounded battery through the impulse machine. Similarly during the second receiving stage, which occurs when segment 655 engages brush 638, all the No. 2 relays in the various registers which are ultimately to be operated will be operated and so on.

After the register relays shown in Fig. 7 have been actuated, it is essential that the controlling sequence switch 700 be advanced and the translator switch be restored since it performs no further function, its registration having been transferred to the relays of Fig. 7. In order to insure that a complete revolution of the impulser may take

place before the advance of sequence switch 700, counting relays 768 to 770 are provided. Referring now to Fig. 6, when segment 657 engages brush 629 a circuit is completed 5 from grounded battery, segment 657, brush 629, conductor 677, inner right-hand armature and front contact of relay 721, winding of relay 771 to ground. Relay 771 is energized and completes a circuit from grounded 10 battery, winding of relay 768, armature and back contact of relay 769, armature and front contact of relay 771 to ground. Relay 768 is energized and completes a locking 15 circuit for itself including the winding of relay 769. The relay 769 is not energized at this time, however, since it is shunted by the presence of direct ground at the armature and contact of relay 771. As soon as segment 657 passes from engagement with 20 brush 629, relay 771 deenergizes and allows counting relay 769 to be energized. When segment 678 engages brush 629, relay 771 is again energized and allows the lower counting 25 relay of the second pair to become energized and prepare a circuit for the upper counting relay of such second pair. As soon as segment 678 passes from engagement with brush 629, relay 771 is deenergized and allows the upper counting relay of the 30 second pair to be energized and prepare a circuit for the lower counting relay of the third and last pair. After the impulser has completed a complete revolution, and again causes segment 657 to engage brush 629, the 35 lower counting relay of the last pair is energized and when segment 657 breaks engagement with brush 629, relay 770 is energized. It is obvious that, regardless of the position of the impulser at the time of the 40 start of the register setting operation, three makes and three breaks of contact at brush 629 must be made before the sequence switch 700 can be advanced out of position 7. It is also apparent that the setting of the relays 45 which constitutes the various registers will take place in proper order and without possibility of wrong settings regardless of the position of the impulse switch at the time that the setting operation is begun.

50 When relay 770 is energized, a circuit is completed from grounded battery, power magnet of sequence switch 700, lower left-hand contact of sequence switch spring 772, right-hand armature and front contact of 55 relay 770 to ground, for moving this sequence switch out of position 7 and into position 8.

As soon as sequence switch 700 leaves position 7, relay 721 is deenergized and completes a circuit from grounded battery, winding of down-drive magnet 679, conductor 680, outer right-hand armature and back contact of relay 721, lower contact of sequence switch spring 722 to ground. The 65 translator switch is returned to its normal

position under the control of magnet 679 and when the translator brush shaft reaches its normal position, as evidenced by the engagement of commutator brush 613 with normal commutator segment 681, a circuit 70 is completed from grounded battery, winding of relay 721, lower left-hand and upper right-hand contacts of sequence switch spring 710, conductor 773, commutator segment 681, brush 613 to ground. Relay 721 75 is energized and opens the circuit of down-drive magnet 679.

The operation of transferring the registration from the relays of Fig. 7 to the relays of Fig. 5 will now be described.

When sequence switch 700 reaches position 7 $\frac{1}{4}$ a circuit is completed from grounded battery, right-hand winding of relay 502 (Fig. 5), conductor 503, lower contacts of sequence switch spring 308, closed due to the fact that sequence switch 300 is in position 6, conductors 309, 310 and 311, terminal 240, brush 241, conductors 242 and 243, upper left-hand and lower right-hand contacts of sequence switch spring 244, conductor 245, 85 upper right-hand contact of sequence switch spring 774, left-hand armature and front contact of relay 734 to ground. Relay 502 is a marginal relay but due to the fact that direct ground is supplied to its right-hand 90 winding it becomes energized and locks up through its left-hand armature to conductor 504 which is grounded at the upper right-hand contact of sequence switch spring 312.

When sequence switch 700 reaches position 8, a circuit is completed from grounded battery, right-hand winding of relay 500 (Fig. 5), conductor 501, upper contacts of sequence switch spring 306, which are closed due to the fact that sequence switch 300 is in position 6, conductor 307, terminal 235, brush 236, conductor 237, lower contact of sequence switch spring 238, conductor 239, upper right-hand contact of sequence switch spring 775, through the right-hand armatures and front contacts of relays 743 and 734 in parallel, conductor 776, right-hand and left-hand windings of relay 777 in series, upper armature and back contact of relay 778 to ground. Relay 777 is energized in this circuit but marginal relay 500 is not energized, due to the fact that the high resistance winding of relay 777 was included in this circuit. Relay 777 upon energization locks up through its inner left-hand armature and front contact and in so doing removes the shunt from about the winding of relay 778, allowing this relay to be energized due to the completion of a circuit extending from grounded battery, resistance 779, upper left-hand contact of sequence switch spring 780, winding of relay 778 to ground. This last mentioned circuit was previously in existence, but relay 778 was shunted by the presence of ground supplied by way of the low-

100

120
125
130

er armature and back contact of relay 778 and the inner left-hand armature and back contact of relay 777.

With sequence switch 700 in position 8, a circuit is also completed from ground, right-hand winding of relay 505, conductor 506, upper contacts of sequence switch spring 313, conductor 314, terminal 246, brush 247, lower contact of sequence switch spring 248, conductor 249, lower contact of sequence switch spring 781, left-hand armature and front contact of relay 743, low resistance 782 to grounded battery. Relay 505 is energized in this circuit and locks up through its left-hand winding and left-hand armature and front contact to grounded conductor 504.

As soon as relay 777 is energized, a circuit is completed from ground, winding of relay 315 (Fig. 3), upper contact of sequence switch spring 316, conductor 321, right-hand winding of marginal relay 507, conductors 508 and 322, terminal 250, brush 251, conductor 252, upper right-hand contact of sequence switch spring 783, conductor 784, high resistance 785, conductor 786, outer left-hand armature and front contact of relay 777, low resistance 787 to grounded battery. Relay 315 is energized in this circuit but relay 507, being marginal, does not become energized due to the inclusion in its circuit of high resistance 785. The energization of relay 315 completes a circuit from grounded battery, power magnet of sequence switch 300, armature and front contact of relay 315, lower left-hand and upper right-hand contacts of sequence switch spring 317, armature and back contact of relay 318 to ground for moving this sequence switch out of position 6 and into position 7.

As soon as sequence switch 300 leaves position 6, the energizing circuit for relay 777 is opened and this relay deenergizes, completing a circuit from grounded battery, power magnet of sequence switch 700, lower contact of sequence switch spring 788, left-hand armature and back contact of relay 789, lower armature and front contact of relay 778, inner left-hand armature and back contact of relay 777, to ground for moving this sequence switch out of position 8 and into position 9. As soon as sequence switch 700 leaves position 8, the circuit of relay 778 is broken at sequence switch spring 780 and this relay deenergizes.

In position 9 and 7 of sequence switches 700 and 300 respectively, the setting of the registers in Fig. 5 is continued. This operation is as follows.

When sequence switch 700 reaches position 8 $\frac{1}{4}$ a circuit is completed from ground, right-hand winding of relay 509, right-hand winding of marginal relay 510, conductor 511, contacts of sequence switch spring 323, conductor 307, terminal 235, brush 236, conductor 237, lower contact of sequence switch

spring 238, conductor 239, upper left-hand contact of sequence switch spring 775, left-hand armature and front contact of relay 765, low resistance 782, to grounded battery. Since only a low resistance is included in this circuit, both relays 509 and 510 are energized in spite of the fact that relay 510 is marginal. These relays upon energization lock up to grounded conductor 504. At the same time a circuit is completed from ground, right-hand winding of relay 512, right-hand winding of marginal relay 513, conductor 514, lower contacts of sequence switch spring 325, conductor 322, terminal 250, brush 251, conductor 252, lower left-hand contact of sequence switch spring 790, left-hand armature and front contact of relay 732, high resistance 791, low resistance 792 to ground. Due to the presence of the high resistance 791 in this circuit, relay 513, which is marginal, does not become energized. Relay 512 does, however, become energized and locks up through its left-hand winding.

When sequence switch 700 reaches position 9, a circuit is completed from grounded battery, left-hand winding of marginal relay 515, conductor 516, lower contacts of sequence switch spring 324, conductor 314, terminal 246, brush 247, contact of sequence switch spring 248, conductor 249, upper right-hand contact of sequence switch spring 781, outer right-hand armature and front contact of relay 732, outer right-hand armature and front contact of relay 765, conductor 793, high and low resistance windings of relay 789 in series to ground through the upper armature and back contact of relay 794. At the same time a parallel path is closed extending through the left-hand armature and front contact of relay 744, upper contact of sequence switch spring 795, conductor 796, low resistance right-hand winding of relay 789 and thence to ground. Relay 789 is energized in this circuit and due to the fact that the last traced parallel path short-circuits the high resistance of the left-hand winding of relay 789, marginal relay 515 (Fig. 5) is allowed to energize. Relay 515 upon energization locks up to grounded conductor 504. Relay 789, upon energization locks up through its inner right-hand armature and front contact and at the same time removes the shunting ground which has been preventing the energization of relay 794. Relay 794 is now energized due to the completion of a circuit from grounded battery, resistance 779, right-hand contact of sequence switch spring 780 and the winding of relay 794 to ground.

The energization of relay 789 completes a circuit from ground, winding of relay 318 (Fig. 3), upper contact of sequence switch spring 320, conductor 326, left-hand wind-

ing of marginal relay 517, conductors 518, 310 and 311, terminal 240, brush 241, conductors 242 and 243, upper left-hand and lower right-hand contacts of sequence 5 switch spring 244, conductor 245, upper left-hand contact of sequence switch spring 774, through the high resistance 785, conductor 786, outer right-hand armature and front contact of relay 789, low resistance 10 787 to grounded battery. Due to the presence of the high resistance 785, relay 517 cannot become energized. Relay 318 does, however, become energized and completes a circuit from grounded battery, power 15 magnet of sequence switch 300, armature and back contact of relay 315, upper left-hand and lower right-hand contacts of sequence switch spring 317, armature and front contact of relay 318, to ground for 20 moving this sequence switch out of position 7 and into position 8.

As soon as sequence switch 300 leaves position 7, relays 318 and 789 are deenergized. The deenergization of relay 789 completes 25 a circuit from grounded battery, power magnet of sequence switch 700, upper contact of sequence switch spring 788, right-hand armature and back contact of relay 777, lower armature and front contact of relay 794, inner right-hand armature and back contact of relay 789 to ground for moving this sequence switch out of position 9 and into position 10. As soon as sequence 30 switch 700 leaves position 9, the holding circuit of relay 794 is broken and this relay deenergizes.

When sequence switch 700 reaches position 9 $\frac{1}{4}$, a circuit is completed from ground, right-hand winding of relay 519, right-hand 40 winding of marginal relay 520, conductor 521, right-hand contact of sequence switch spring 327, left-hand contact of sequence switch spring 313, conductor 314, terminal 246, brush 247, contact of sequence switch 45 spring 248, conductor 249, upper left-hand contact of sequence switch spring 781, left-hand armature and front contact of relay 733, high resistance 797, low resistance 782 to grounded battery. Due to the presence 50 of high resistance 797 in this circuit, relay 520 does not become energized. Relay 519 does, however, become energized and locks up to grounded conductor 504.

When sequence switch 700 reaches position 55 10, a circuit is completed from grounded battery, left-hand winding of marginal relay 522, conductor 523, upper contact of sequence switch spring 328, left-hand contact of sequence switch spring 306, conductor 307, terminal 235, brush 236, conductor 237, contact of sequence switch spring 238, conductor 239, lower left-hand contact of sequence switch spring 775, outer right-hand armature and front contact of 60 65 relay 733, conductors 798 and 776, high and

low resistance windings of relay 777, outer armature and back contact of relay 778 to ground. Due to the fact that the high resistance right-hand winding of relay 777 has been included in this circuit, marginal 70 relay 522 does not become energized. Relay 777 does, however, become energized and locks up through its inner left-hand armature and front contact and allows relay 778 to operate in the manner previously described. The energization of relay 777 completes a circuit from ground, winding of relay 315 (Fig. 3), lower contacts of sequence switch spring 319, conductor 329, right-hand winding of marginal relay 524, conductors 508 and 322, terminal 250, brush 251, conductor 252, upper right-hand contact of sequence switch 783, conductor 784, high resistance 785, conductor 786, outer left-hand armature and front contact of relay 777, low resistance 787 to grounded battery. Relay 315 is energized in this circuit, but relay 524 cannot become energized due to the presence of high resistance 785. There is in addition, however, a circuit extending from conductor 252 by way of the upper left-hand contact of sequence switch spring 790, left-hand armature and front contact of relay 759 and thence by way of conductor 799 to conductor 786 and to grounded battery 95 as previously described. It is to be observed that this last traced circuit short circuits the high resistance 785 and renders it ineffective. Therefore, relay 524 is energized and locks up through its left-hand armature. 100

The energization of relay 315 completes a circuit from grounded battery, power magnet of sequence switch 300, armature and front contact of relay 315, lower left-hand and upper right-hand contacts of sequence switch spring 317, armature and back contact of relay 318 to ground for moving this sequence switch out of position 8 and into position 9. As soon as sequence switch 105 300 leaves position 8, relays 315 and 777 are deenergized. Relay 777 upon deenergization completes a circuit from grounded battery, power magnet of sequence switch 700, lower right-hand contact of sequence switch spring 788, left-hand armature and back contact of relay 789, lower armature and front contact of relay 778, inner left-hand armature and back contact of relay 777 to ground, for moving this sequence switch out of position 10 and into position 11. As soon 110 115 as sequence switch 700 leaves position 10, relay 778 is deenergized.

When sequence switch 700 reaches position 10 $\frac{1}{4}$, a circuit is completed from ground, right-hand winding of relay 527, right-hand 120 winding of marginal relay 528, conductor 529, lower contact of sequence switch spring 328, upper contact of sequence switch spring 306, conductor 307, terminal 235, brush 236, conductor 237, contact of sequence switch 125 130

spring 238, conductor 239, lower right-hand contact of sequence switch spring 775, left-hand armature and front contact of relay 766, low resistance 782 to grounded battery.

5 Since only a low resistance is included in this circuit, relays 527 and 528 are both energized and lock up through their left-hand windings. At the same time a circuit is completed from grounded battery, winding of relay 530, conductor 531, left-hand contacts of sequence switch spring 325, conductor 322, terminal 250, brush 251, conductor 252, left-hand contact of sequence switch spring 783, left-hand armature and front contact of relay 760 to ground. Relay 530 is energized in this circuit and locks up through its left-hand armature and front contact to grounded conductor 504.

10 When sequence switch 700 reaches position 11, a circuit is completed from grounded battery, left-hand winding of marginal relay 525, conductor 526, left-hand contact of sequence switch spring 327, left-hand contact of sequence switch spring 313, conductor 314, terminal 246, brush 247, contact of sequence switch spring 248, conductor 249, contact of sequence switch spring 781, outer right-hand armature and front contact of relay 766, conductor 793, high and low resistance 30 windings of relay 789 in series, upper armature and back contact of relay 794 to ground. Relay 789 is energized in this circuit, but due to the fact that the high resistance left-hand winding of relay 789 was included in 35 this circuit, marginal relay 525 does not become energized. Relay 789 upon energization locks up through its inner right-hand armature and front contact and in doing so removes the shunt from about the winding 40 of relay 794, which relay therefore becomes energized. The energization of relay 789 completes a circuit from ground, winding of relay 318 (Fig. 3), upper contacts of sequence switch spring 319, conductor 330, right-hand winding of marginal relay 532, conductors 518, 310 and 311, terminal 240, brush 241, conductors 242 and 243, upper 45 left-hand and lower right-hand contacts of sequence switch spring 244, conductor 245, upper left-hand contact of sequence switch spring 774, high resistance 785, conductor 786, outer right-hand armature and front contact of relay 789, low resistance 787 to grounded battery. An alternate path is 50 closed at the same time extending from conductor 245 by way of the lower right-hand contact of sequence switch spring 774, left-hand armature and front contact of relay 761 to conductor 786 and thence to grounded 55 battery as described. Resistance 785 is short circuited by this last traced path and therefore relays 532 and 318 are both energized.

The energization of relay 318 completes a circuit from grounded battery, power mag- 60 net of sequence switch 300, armature and

back contact of relay 315, upper left-hand and lower right-hand contacts of sequence switch spring 317, armature and front contact of relay 318 to ground, to move sequence switch 300 out of position 9 and into position 10. When sequence switch 300 leaves position 9, relays 318 and 789 are deenergized, but relay 532 remains energized due to the fact that it has closed a locking circuit through its left-hand winding and left-hand armature and front contact to grounded conductor 504.

The deenergization of relay 789 completes a circuit from grounded battery, power magnet of sequence switch 700, upper right-hand contact of sequence switch spring 788, right-hand armature and back contact of relay 777, lower armature and front contact of relay 794, inner right-hand armature and back contact of relay 789 to ground, for moving this sequence switch out of position 11 and into position 12. As soon as sequence switch 700 leaves position 11, relay 794 is deenergized. At the same time the locking circuits of the various register relays of Fig. 7 are opened at the lower contacts of sequence switch spring 719 and all these relays are restored to their normal condition.

Relays 764, 800, 801 and 757 are used to determine the selection of one of a number of counting devices. One of these counting devices is operated each time the register relays of Fig. 7 are put into use. The mechanical construction of these counting devices may be similar to that of a message register. In the present case the counting device connected to lead 802 would be actuated over a circuit extending from grounded battery, through such counting device (not shown), outer right-hand armature and back contact of relay 801 left-hand armature and front contact of relay 757 to ground at the upper left-hand contact of sequence switch spring 719. This counting operation takes place while the sequence switch 700 is being advanced through positions 9 to 11 inclusive. It is obvious that by operating various combinations of the four relays shown, seven counting devices may be used to record how many of each of seven kinds of calls have been set up on the registering device.

When sequence switch 700 reaches position 12, a circuit is completed from grounded battery, power magnet of sequence switch 200, upper left-hand contact of sequence switch spring 206, conductor 253, contact of sequence switch spring 803 to ground, for moving sequence switch 200 out of position 6 and into position 8.

When sequence switch 200 reaches position 8, a circuit is completed from grounded battery, power magnet of sequence switch 700, conductor 705, lower right-hand contact

of sequence switch spring 772, conductor 804, contact of sequence switch spring 254 to ground, for moving this sequence switch out of position 12 and into position 16.

5 In position 16 of sequence switch 700 the keys of the operator's key set are released by means of magnets (not shown) which are actuated in position 16 of the sequence switch. As soon as all of the keys have been released, circuits (not shown, but which are familiar to those skilled in the art) are completed for moving sequence switch 700 out of position 16 and into position 1. The apparatus shown in Figs. 6 and 7 has now all 15 been restored and is ready for reuse.

The positioning of the class controlling sequence switch 534 will now be described. This sequence switch has no normal position, but remains in whatever position it was last 20 set until circuits are completed for moving it into a new position. The position in which the class sequence switch stopped is determined by which relays of the relays 502, 507, 505 and 500 have been actuated. It 25 will be recalled that in the present case, relays 502 and 505 have been actuated. It will be assumed that when the sender was last used, the sequence switch 534 was resting in position 16. As soon as sequence 30 switch 300 reaches position 7 at which time the class controlling relays above mentioned have been selectively positioned in accordance with the proper registration, sequence switch 534 will be moved out of position 16, 35 through intermediate positions into position 14, which is the position in which this sequence switch controls the operation of the sender in such a manner that a call may be directed to a local desk. A circuit is 40 completed from grounded battery, power magnet of sequence switch 534, upper left-hand contact of sequence switch spring 535, right-hand armature and front contact of relay 502, conductor 536, lower contact of 45 sequence switch spring 312 to ground. Sequence switch 534 moves into position 17 from which it is immediately moved due to the completion of a circuit from grounded battery, power magnet of sequence switch 534, upper right-hand contact of sequence 50 switch spring 537, right-hand armature and back contact of relay 500 and thence to ground over conductor 536. The sequence switch moves into position 1 from which position it is moved by means of a circuit identical with that traced for moving it out of position 17. The sequence switch is moved 55 out of position 2 by means of a circuit extending from the upper left-hand contact of sequence switch spring 537, right-hand armature and front contact of relay 505 to 60 grounded conductor 536. The control of the sequence switch is alternated between the upper right-hand and upper left-hand contacts 65 of sequence switch 537 until the sequence

switch reaches position 10, at which time its power circuit is extended from the upper right-hand contact of sequence switch spring 535, right-hand armature and back contact of relay 507 to grounded conductor 536, for moving this sequence switch out of position 10 and into position 11. It is then moved out of position 11 by way of a circuit closed through the upper right-hand contact of sequence switch spring 537. From position 12 the sequence switch is moved into position 13 by means of a circuit closed through the upper left-hand contact of sequence switch spring 535 and the right-hand armature and front contact of relay 502. The upper right-hand contact of sequence switch spring 537 then serves to advance the sequence switch out of position 13 and into position 14. An inspection of the circuits 25 will show that in position 14 there is no circuit in existence for advancing the sequence switch 534. It therefore, remains in this position. Relay 538 is energized in parallel with the power magnet of sequence 30 switch 534 during the setting movement of the class register switch. The purpose of this is to prevent the closing of the fundamental circuit before the class register has been fully positioned. As soon as the class 35 register has been fully positioned, relay 538 deenergizes and closes a circuit from grounded battery, power magnet of sequence switch 400 (Fig. 4), lower right-hand contact of sequence switch spring 401, conductor 402, contacts of sequence switch spring 334, conductor 335, armature and back contact of relay 538 to ground for moving this sequence switch out of position 1 and into 40 position 4.

With sequence switch 400 in position 4, sequence switch 300 in position 10 and sequence switch 200 in position 8, the fundamental circuit for controlling the district brush selecting operation is completed, it 45 being remembered that sequence switch 100 is at this time in position 5.

The fundamental circuit extends from grounded battery, left-hand winding of relay 106, lower right-hand contact of sequence switch spring 121, lower left-hand contact of sequence switch spring 125, conductor 231, terminal 230, brush 229, inner right-hand armature and front contact of relay 228, upper left-hand and lower right-hand contacts of sequence switch spring 222, conductor 242, brush 241, terminal 240, conductors 311 and 331, contact of sequence switch spring 332, conductor 333, contacts of sequence switch spring 403, winding of stepping relay 404, armature and back contact of the 0' counting relay, conductor 405, contacts of sequence switch spring 336, conductor 337, upper contact of sequence switch spring 406 to ground. Relay 106 and stepping re- 50

lay 404 are energized in this circuit. The energization of relay 106 completes a circuit from grounded battery, power magnet of sequence switch 100, conductor 117, left-hand contacts of sequence switch spring 124, inner right-hand armature and front contact of relay 106, upper contacts of sequence switch spring 109 to ground, for moving this sequence switch out of position 5 and 10 into position 6.

In position 6 of sequence switch 100, relay 106 is maintained energized by means of a circuit closed through its left-hand winding and left-hand armature and front contact 15 and the upper right-hand contact of sequence switch spring 121 to ground at spring 406 over the path described.

With sequence switch 100 in position 6, and with relay 106 energized, a circuit is completed from grounded battery, winding of up-drive magnet 126, upper right-hand and lower left-hand contacts of sequence switch spring 124, right-hand armature and front contact of relay 106, upper contacts of 25 sequence switch spring 109 to ground.

Referring now to Fig. 4, it will be noted that the energization of stepping relay 404 completed a circuit from ground, upper left-hand contact of sequence switch spring 407, 30 armature and front contact of relay 404, contact of sequence switch spring 408, conductor 409, left-hand contact of sequence switch spring 338, conductor 339, lower left-hand contact of sequence switch spring 410, lower 35 left-hand contact of sequence switch spring 411, conductor 412, right-hand armature and front contact of relay 509, left-hand armature and front contact of relay 515, outer right-hand armature and front contact of relay 510, thence to the armature and back contact 40 of the No. 3' counting relay (Fig. 4), winding of the No. 3 counting relay, contact of sequence switch 413 to grounded battery. The No. 3 counting relay is energized in this 45 circuit and completes a locking circuit for itself including the winding of the No. 3' counting relay. The No. 3' counting relay does not, however, become energized since its winding is shunted by the presence of direct 50 ground controlled at the armature of stepping relay 404.

In response to the energization of up-drive magnet 126, the district brush shaft is moved upwardly. As soon as commutator 55 brush 127 engages a conducting segment of commutator 128, stepping relay 404 is shunted down due to the completion of a circuit extending from grounded battery, left-hand winding of relay 106, left-hand armature 60 and front contact of relay 106, upper right-hand contact of sequence switch spring 121, lower right-hand contact of sequence switch spring 125, commutator 128, commutator brush 127 to ground. Relay 106 is 65 maintained energized in this circuit but re-

lay 404 is deenergized and causes the energization of the No. 3' counting relay in the well-known manner. As soon as commutator brush 127 engages an insulating segment of commutator 128, the shunt path to ground is opened and relay 404 is again energized to cause the energization of the No. 2 counting relay. The advance of the district brush shaft continues and the counting relays are successively actuated. After the 75 brush shaft has been advanced three steps a circuit is completed from grounded battery, winding of the No. 0 counting relay, armature and back contact of relay 414, conductor 415 and thence through the right-hand armatures and front contacts of the Nos. 1', 2' and 3' counting relays in series to ground at sequence switch spring 407. When the district switch has completed its fourth brush selecting step, relay 404 is again de- 80 energized and allows the No. 0' counting relay and relay 416 in parallel therewith to become energized. The energization of the 0' counting relay opens the lower branch of the fundamental circuit and since commutator brush 127 is now engaging an insulating segment of commutator 128, the locking circuit of relay 106 is broken and this relay deenergizes and completes a circuit from 85 grounded battery, winding of power magnet 90 of sequence switch 100, conductor 117, lower contacts of sequence switch spring 114, inner right-hand armature and back contact of relay 106, upper contacts of sequence switch spring 109 to ground, for moving this 95 sequence switch out of position 6 and into position 7. The deenergization of relay 106 also opens the circuit of up-drive magnet 126 and causes the district brush shaft to be brought to rest in a position such 100 that upon subsequent upward movement of the brush shaft the fourth set of brushes will be tripped.

In position 7 of sequence switch 100, a circuit is completed from grounded battery, 110 winding of trip magnet 197, right-hand contacts of sequence switch spring 109 to ground. The trip rod is actuated in the well-known manner.

Referring to the sender circuit in Fig. 4, 115 the energization of relay 416 completes a circuit extending from grounded battery, power magnet of sequence switch 400, upper right-hand contact of sequence switch spring 401, armature and front contact of relay 416 120 to ground for moving this sequence switch out of position 4 and into position 6.

With sequence switch 100 in position 7 and sequence switch 400 in position 6 the fundamental circuit is again completed to 125 control group selection at the district switch shown in Fig. 1. This circuit is identical with that described for controlling brush selection. Relay 106 upon energization locks up as before and causes the advance 130

of sequence switch 100 out of position 7 and into position 8 by means of circuits identical with those traced for moving this sequence switch from position 5 to position 6. Relay 404 is again energized upon the second completion of the fundamental circuit. It is to be noted that when sequence switch 400 left position 4 the locking circuits of the counting relays were opened at sequence switch springs 413 and 407. In position 6 of sequence switch 400, relay 414 is energized due to the existence of a circuit extending from grounded battery, winding of relay 414, upper contacts of sequence switch spring 417, conductor 418, right-hand armature and front contact of relay 524, conductor 539, contact of sequence switch spring 340 to ground.

The energization of relay 404 at this time completes a circuit from ground, upper left-hand contact of sequence switch spring 407, armature and front contact of relay 404, contact of sequence switch spring 408, conductor 409, left-hand contact of sequence switch spring 338, conductor 339, lower left-hand contact of sequence switch spring 410, lower right-hand contact of sequence switch spring 411, conductor 419, right-hand armature and front contact of relay 519, left-hand armature and back contact of relay 522, inner right-hand armature and back contact of relay 520, thence to conductor 415 (Fig. 4) right-hand armature and front contact of relay 414, armature and back contact of the No. 9' counting relay, the winding of the No. 9 counting relay, contact of sequence switch 413 to grounded battery. The No. 9 counting relay is energized in this circuit and completes a locking circuit for itself including the No. 9' counting relay. The No. 9' counting relay is not energized, however, due to the shunt circuit extending to ground by way of the armature and front contact of relay 404.

In position 8 of sequence switch 100 and with relay 106 energized the circuit of up-drive magnet 126 is again completed and the district brush shaft is moved upward in its group selecting movement. When commutator brush 127 engages a conducting segment of group commutator 129, stepping relay 404 is shunted by a path extending by way of the upper left-hand contact of sequence switch spring 125, commutator 129, commutator brush 127 to ground. The de-energization of relay 404 allows the No. 9' counting relay to be energized. As the brush shaft is moved upwardly the action of commutator brush 127 on commutator 129 causes the successive actuation of the counting relays. After the No. 5' counting relay has been energized, the next energization of stepping relay 404 completes a circuit from grounded battery, winding of the

and front contact of relay 414, and thence through the armatures and front contacts of counting relays Nos. 5' to 9' inclusive and thence to ground over the path previously described. When commutator brush 127 engages the next insulating segment of commutator 129, the No. 0' counting relay and relay 416 in parallel therewith are energized. The energization of the 0' counting relay opens the lower branch of the fundamental circuit and since at this time commutator brush 127 is in contact with an insulating segment, the upper branch of the holding circuit of relay 106 is opened and this relay deenergizes, completing a circuit for moving sequence switch 100 out of position 8 and into position 9, which is identical with the circuit previously traced for moving this sequence switch from position 6 into position 7. In the sender, the energization of relay 416 completes a circuit extending from grounded battery, power magnet of sequence switch 400, upper right-hand contact of sequence switch spring 401, armature and contact of relay 416 to ground, for moving this sequence switch out of position 6 and into position 10.

Since the call is to be directed to a local desk, an office selector need not be operated. Therefore sequence switch 400 is moved through positions 10 and 12, in which positions office brush and office group selection, respectively, would normally take place. This is accomplished due to the fact that relay 530 (Fig. 5) has been energized. Therefore, as soon as sequence switch 400 reaches position 8, a circuit is completed from grounded battery, winding of the No. 0 counting relay, it being remembered that all the counting relays were deenergized as soon as sequence switch 400 left position 6, thence through the windings of the No. 0' counting relay and relay 416 in parallel, conductor 420, contact of sequence switch spring 421, conductor 422, right-hand armature and front contact of relay 530, conductor 541, upper left-hand contact of sequence switch spring 312 to ground. The counting relays Nos. 0 and 0' and relay 416 are energized in this circuit. Relay 416 completes a circuit extending from grounded battery, power magnet of sequence switch 400, upper right-hand contacts of sequence switch spring 401, armature and front contact of relay 416 to ground, for moving this sequence switch through position 10 and 12 and into position 14. Since no further selections are to be controlled by the sender, the sequence switch 400 is moved out of position 14 and into position 15 by means of a circuit extending from grounded battery, power magnet of sequence switch 400, upper right-hand contact of sequence switch spring 423, conductor 424, contact of class sequence switch spring 542 to ground.

65 No. 0 counting relay, left-hand armature

With sequence switch 400 in position 15, a circuit is completed from grounded battery, power magnet of sequence switch 300, upper left-hand contact of sequence switch 5 spring 305, conductor 343, lower left-hand contact of sequence switch spring 407, to ground, for moving this sequence switch out of position 10 and into position 11.

In the practical operation of the system, 10 relay call indicator pulses would be sent after the district and office switches have been positioned or else incoming and final switches would be operated under the control of the sender during a second revolution 15 of the controlling sequence switch 400. The circuits have been simplified by omitting certain ones of the controlling circuits by which these operations would be accomplished, since they are not pertinent to the 20 invention.

With the class sequence switch in position 14, the controlling sequence switch in Fig. 2 is advanced when sequence switch 300 reaches position 11 and due to the advance 25 of sequence switch 200, the fundamental circuit cannot again be completed. The advance of sequence switch 200 is controlled by relay 204 which, under the conditions above named, is energized due to the closure 30 of a circuit extending from grounded battery, right-hand winding of relay 204, upper contacts of sequence switch spring 238, conductor 237, brush 236, terminal 235, conductors 307 and 344, class sequence switch contact 543, conductor 544, lower contacts of sequence switch spring 425, conductor 426, right-hand contact of sequence switch spring 345 to ground. The resulting energization 35 of relay 204 completes a circuit extending from grounded battery, power magnet of sequence switch 200, upper right-hand contact of sequence switch spring 206, inner right-hand armature and front contact of relay 204 to ground for moving this sequence switch out of position 8 and into 40 position 9.

The above traced circuit for relay 204 is in existence for only a short space of time, but is nevertheless closed for a sufficient interval to cause sequence switch 200 to be advanced. The short duration of the closure of this circuit is due to the fact that with sequence switch 300 in position 11 a circuit is completed from grounded battery, 45 power magnet of sequence switch 400, lower left-hand contact of sequence switch spring 401, conductor 427, contact of sequence switch spring 346, to ground, for moving this sequence switch out of position 15 and into position 16. Sequence switch 400 is then immediately moved out of position 16 50 and into position 18 by means of a circuit extending from grounded battery, power magnet of sequence switch 400, upper right-hand contact of sequence switch 423, con-

ductor 424, contact of class sequence switch spring 542 to ground. In position 18 of sequence switch 400, a circuit is completed from grounded battery, power magnet of sequence switch 300, upper right-hand contact of sequence switch spring 305, conductor 347, lower right-hand contact of sequence switch spring 407 to ground for moving this sequence switch out of position 11 and into 70 position 18.

As soon as sequence switch 300 reaches position 13 a circuit is completed from grounded battery, power magnet of sequence switch 400, upper left-hand contact of sequence switch spring 423, conductor 428, 80 left-hand contact of sequence switch spring 345 to ground, for moving this sequence switch out of position 18 and into position 1. A circuit is thereupon completed from grounded battery, power magnet of sequence 85 switch 300, lower right-hand and upper left-hand contacts of sequence switch spring 303, conductor 348, lower contact of sequence switch spring 406 to ground, for moving sequence switch 300 out of position 18 and into 90 position 1. When sequence switch 300 leaves position 12, ground is removed from conductor 504 to allow all the register relays to be restored to their normal condition. When sequence switch 300 leaves position 18, relay 95 301 is deenergized and the busy ground condition is removed from test terminal 218 to render the sender selectable to other sender selectors. The apparatus on Figs. 3, 4 and 5 has now all been restored to its normal condition and is ready for reuse.

Referring now to Fig. 1, it will be remembered that after group selection was accomplished, the sequence switch 100 was advanced into position 9. A circuit is then 105 completed from grounded battery, left-hand winding of relay 106, lower right-hand contact of sequence switch spring 121, conductor 122, lower right-hand contact of sequence switch spring 123 to ground. Relay 106 is 110 energized in this circuit and locks up through its right-hand winding to test brush 130, provided that the first trunk in the selected group is busy, over a circuit extending from grounded battery, right-hand winding 115 of relay 106, upper left-hand contact of sequence switch spring 110, outer right-hand armature and front contact of relay 106, lower left-hand and upper right-hand contacts of sequence switch spring 111, test 120 brush 130, test terminal 131 to ground. At the same time a circuit is completed from grounded battery, power magnet of sequence switch 100, conductor 117, left-hand contacts of sequence switch spring 124, inner 125 right-hand armature and front contact of relay 106, upper contacts of sequence switch spring 109 to ground for moving this sequence switch out of position 9 and into position 10.

In position 10 of sequence switch 100, a circuit is completed from grounded battery, winding of up-drive magnet 126, upper right-hand and lower left-hand contacts of sequence switch spring 124, inner right-hand armature and front contact of relay 106, upper contacts of sequence switch spring 109 to ground. Magnet 126 is energized and advances the district brush shaft in its trunk hunting movement. As soon as test brush 130 encounters the test terminal of an idle trunk, which will be characterized by the absence of ground potential on such test terminal, the circuit through the right-hand winding of relay 106 is broken, but relay 106 remains energized due to the existence of a circuit from grounded battery, left-hand winding of relay 106, left-hand armature and front contact of relay 106, upper right-hand contact of sequence switch spring 121, upper right-hand contact of sequence switch spring 125, conducting segment of commutator 132, commutator brush 133 to ground. When commutator brush 133 engages an insulating segment of commutator 132, at which time the brush set is accurately centered on the terminals of an idle trunk, relay 106 is deenergized and opens the circuit of up-drive magnet 126 to cause the brush shaft to be brought to rest. At the same time the deenergization of relay 106 completes a circuit from grounded battery, power magnet of sequence switch 100, lower contacts of sequence switch 114, inner right-hand armature and back contact of relay 106, upper contacts of sequence switch spring 109 to ground for moving this sequence switch out of position 10 and into position 11.

In position 11 of sequence switch 100, in the normal operation of the system, the fundamental circuit is extended to the tip and ring conductors to control subsequent selections. Since in the type of call which is being considered at present, no apparatus beyond the district switch is to be operated, and since in view of this fact sequence switch 200 has been advanced to position 9, a circuit is completed from grounded battery, left-hand winding of relay 106, lower contact of sequence switch spring 134, conductor 120, terminal 232, brush 233, outer left-hand armature and front contact of relay 228, upper contact of sequence switch spring 234 to ground. Relay 106 is energized in this circuit and completes a circuit from grounded battery, power magnet of sequence switch 100, conductor 117, left-hand contacts of sequence switch spring 124, inner right-hand armature and front contact of relay 106, upper contacts of sequence switch spring 109 to ground for moving this sequence switch out of position 11 and into position 13, which is the talking position.

The call has now been extended to a local desk and conversation between the operator thereat and the calling subscriber may take place.

As soon as sequence switch 100 leaves position 11, the locking circuit of relay 208 is opened at the lower left-hand contact of sequence switch spring 115 and this relay deenergizes, causing in turn the deenergization of relay 228. A circuit is thereupon completed from grounded battery, power magnet of sequence switch 200, upper contact of sequence switch spring 255, outer right-hand armature and back contact of relay 228, to ground, for moving this sequence switch out of position 9 and into position 15.

In position 15 of sequence switch 200, a circuit is completed from grounded battery, winding of down-drive magnet 256, lower contacts of sequence switch spring 209 to ground. The cord finder brush shaft is returned to its normal position under the control of magnet 256 and when it reaches its normal position a circuit is completed from grounded battery, power magnet of sequence switch 200, conductor 257, lower right-hand and upper left-hand contacts of sequence switch spring 258, normal commutator segment 259, commutator brush 215 to ground for moving this sequence switch out of position 15 and into position 16.

In positions 15 and 16 of sequence switch 200, a circuit is completed from grounded battery, winding of sender selector down drive magnet 260, upper right-hand and lower left-hand contacts of sequence switch spring 244, inner right-hand armature and back contact of relay 204 to ground. The sender selector brush shaft is restored to its normal position under the control of magnet 260. When it reaches its normal position a circuit is completed from grounded battery, right-hand winding of relay 204, lower contact of sequence switch spring 270, conductor 261, normal commutator segment 262, commutator brush 224 to ground. Relay 204 is energized and completes a circuit from grounded battery, power magnet of sequence switch 200, upper right-hand contact of sequence switch spring 206, inner right-hand armature and front contact of relay 204 to ground for moving this sequence switch out of position 16 and into position 1. If the sender selector brush shaft is the first to reach its normal position, relay 204 is energized and at its inner right-hand armature opens the circuit of magnet 260 to prevent the constantly rotating power drum from unnecessarily wearing on the driving ribbon. As soon as the cord finder is restored the sequence switch advances into position 16 from which it is then immediately moved into position 1 by means of the circuit above described.

When conversation is completed and connection is no longer desired, the "A" operator is informed by means of well-known supervisory signals (not shown) that connection is no longer desired. She thereupon removes the plug from the outgoing end of the trunk leading to Fig. 1, thus causing the deenergization of relay 104. A circuit is thereupon completed from grounded battery, left-hand winding of relay 106, lower right-hand contact of sequence switch spring 121, conductor 122, upper left-hand contact of sequence switch spring 123, right-hand armature and back contact of relay 104 to ground. Relay 106 is energized and completes a circuit from grounded battery, through lamp 108, left-hand contacts of sequence switch spring 109, inner right-hand armature and front contact of relay 106, upper right-hand and lower left-hand contacts of sequence switch spring 110 through an interrupter 136 to ground. The flashing of lamp 108 informs the cordless operator that connection is no longer desired and she thereupon depresses her disconnect key 137, thus completing a circuit from grounded battery, power magnet of sequence switch 100, lower left-hand contact of sequence switch spring 113, closed contacts of key 137 to ground for moving this sequence switch out of position 13 and into position 18.

In position 18 of sequence switch 100, a circuit is completed from grounded battery, winding of down-drive magnet 138, left-hand contacts of sequence switch spring 139, lower contacts of sequence switch spring 111 to ground. The district brush shaft is restored to its normal position under the control of magnet 138. When the brush shaft reaches its normal position, a circuit is completed from grounded battery, power magnet of sequence switch 100, upper right-hand contact of sequence switch spring 113, normal commutator segment 140, commutator brush 133 to ground for moving this sequence switch out of position 18 and into position 1.

All the parts of the apparatus have now been restored to their normal positions and are ready for reuse.

What is claimed is:

1. In a telephone exchange system, subscribers' lines, automatic switches to be used in establishing inter-connections between said lines, a plurality of variably operable primary registering devices, means to selectively position said primary registering devices, a progressively operable switch, means to position said switch under the joint control of said primary registering devices, a plurality of secondary registering devices, means controlled in accordance with the position assumed by said switch for setting said secondary registering devices, and means to selectively operate said automatic switches under the control of said secondary registering devices.
2. In a telephone exchange system, subscribers' lines, automatic switches to be used in establishing inter-connections between said lines, a plurality of primary registering devices, means to selectively position said primary registering devices, a progressively operable switch, means to position said switch under the joint control of said primary registering devices, a plurality of secondary registering devices, means controlled in accordance with the position assumed by said secondary registering devices, a plurality of tertiary registering devices, means to position said tertiary registering devices, in accordance with the position assumed by said secondary registering devices, and means to selectively operate said automatic switches under the control of said tertiary registering devices.
3. In a telephone exchange system, subscribers' lines, automatic switches to be used in establishing inter-connections between said lines, a plurality of sets of primary registering devices, means to selectively position a desired one of said sets of primary registering devices, a multi-position switch individual to each set of primary registering devices, means to position the associated multi-position switch under the control of said actuated set of primary registering devices, a set of secondary registering devices individual to each of said switches, means common to said multi-position switches and controlled in accordance with the position assumed by said actuated switch for setting said secondary registering devices, and means to selectively operate said automatic switches under the control of said secondary registering devices.
4. In a telephone exchange system, subscribers' lines, automatic switches to be used in establishing inter-connections between said lines, a plurality of sets of primary registering devices, means to selectively position a desired one of said sets of primary registering devices, a multi-position switch individual to each set of primary registering devices, means to position the associated multi-position switch under the control of said actuated set of said primary registering devices, a set of secondary registering devices individual to each of said switches, means common to said multi-position switches and controlled in accordance with the position assumed by said actuated switch for setting the associated set of secondary registering devices, a plurality of tertiary registering devices, means to position said tertiary registering devices in accordance with the position assumed by said actuated set of secondary registering devices, and means to selectively operate said automatic switches under the control of said tertiary registering devices.

switches under the control of said tertiary registering devices.

5. In a telephone exchange system, subscribers' lines, automatic switches to be used in establishing inter-connections between said lines, a plurality of sets of primary registering devices, means to selectively position one of said sets of primary registering devices, a multi-position switch individual to each set of primary registering devices, means to position the associated multi-position switch under the control of said actuated set of primary registering devices, a set of secondary registering devices associated with each of said switches, an impulse sending device common to said multi-position switches for setting said secondary registering devices in accordance with the position assumed by said actuated switch, and means to selectively operate said automatic switches under the control of said secondary registering devices.

6. In a telephone system, subscribers' lines, automatic switches to be used in establishing interconnections between said lines, a plurality of sets of primary registering devices, means to selectively position a desired one of said sets of primary registering devices, a multi-position switch individual to each set of primary registering devices, means to position the associated multi-position switch under the control of said actuated set of primary registering devices, a set of secondary registering devices, individual to each of said multi-position switches, means common to said multi-position switches and controlled in accordance with the position assumed by said actuated switch for setting the associated set of secondary registering devices, a plurality of tertiary registering devices, control circuits extending from said secondary registering devices to said tertiary registering devices, means to position said tertiary registering devices by means of current impulses transmitted over said control circuits in accordance with the position assumed by said actuated set of secondary registering devices and means to selectively operate said automatic switches under the control of said tertiary registering devices.

7. In a telephone exchange system, subscribers' lines, automatic switches to be used in establishing interconnections between said lines, a plurality of sets of primary registering devices, means to selectively position a desired one of said sets of primary registering devices, a multi-position switch individual to each set of primary registering devices, means to position the associated switch under the control of said actuated set of primary registering devices, a set of secondary registering devices individual to each of said switches, means common to said multi-position switches and controlled in

accordance with the position assumed by said actuated switch for setting the associated set of secondary registering devices, tertiary registering devices, control circuits extending to said tertiary registering devices from said actuated set of secondary registering devices, a multi-position progression switch associated with said actuated set of secondary registering devices, means to position said tertiary registering devices by means of current impulses transmitted over said controlling circuits in successive positions of said progression switch, and means to selectively operate said automatic switches under the control of said tertiary registering devices.

8. In a telephone exchange system, a plurality of primary registering devices, means to selectively position said primary registering devices, a multi-position switch, means to position said switch under the joint control of said primary registering devices, a plurality of secondary registering devices, means controlled in accordance with the position assumed by said switch for setting said secondary registering devices, means to restore said switch to its normal position, a progression measuring device, and means under the control of said progression measuring device to prevent the restoration of said switch before said secondary registers have been completely set.

9. In a telephone exchange system, subscribers' lines, automatic switches to be used in establishing interconnections between said lines, a plurality of primary registering devices, means to selectively position said primary registering devices, a multi-position switch, means to position said switch under the joint control of said primary registering devices, a plurality of secondary registering devices, means controlled in accordance with the position assumed by said switch for setting said secondary registering devices, means to restore said switch to its normal position, a progression measuring device comprising a plurality of successively operable relays, and means to render said restoring means effective upon the energization of that one of said relays which is last to be operated.

10. In a telephone exchange system, an automatic switch, means to position said switch, means to restore said switch to its normal position, a progression measuring device comprising a plurality of successively operable relays, and means to put said restoring means into operation when the last one of said relays has been energized.

11. In a telephone exchange system, subscribers' lines, automatic switches to be used in establishing interconnections between said lines, a plurality of sets of primary registering devices, means to selectively position one of said sets of primary registering de-

- vices, a multi-position switch individual to each set of primary registering devices, means to position the associated switch under the control of said actuated set of primary registering devices, a set of secondary registering devices associated with each of said switches, a continuously operating impulse generating device common to said multi-position switches for setting said secondary registering devices in accordance with the position assumed by said actuated switch, and means to selectively operate said automatic switches under the control of said secondary registering devices.
12. In a telephone exchange system, subscribers' lines, automatic switches to be used in establishing interconnections between said lines, a plurality of sets of primary registering devices, means to selectively position one of said sets of primary registering devices, a multi-position switch individual to each set of primary registering devices, means to position the associated switch under the control of said actuated set of primary registering devices, a set of secondary registering devices associated with each of said switches, a continuously power-driven rotating impulse generating device common to said multi-position switches for setting said secondary registering devices in accordance with the position assumed by said actuated switch, and means to selectively operate said automatic switches under the control of said secondary registering devices.
13. In a telephone exchange system, subscribers' lines, automatic switches to be used in establishing interconnections between said lines, a plurality of primary registering devices, means to selectively position said primary registering devices, a multi-position switch, means to position said switch under the joint control of said primary registering devices, a secondary registering device comprising a plurality of groups of relays, there being an equal number of relays in each of said groups, energizing circuits for said relays, means to simultaneously prepare the energizing circuits of a set of corresponding relays in all groups, means to selectively complete circuits for desired ones of said corresponding relays in accordance with the position assumed by said switch, means to complete locking circuits for said relays, and means to selectively operate said automatic switches under the control of said secondary registering devices.
14. In a telephone exchange system, subscribers' lines, automatic switches to be used in establishing interconnections between said lines, a plurality of primary registering devices, means to selectively position said primary registering devices, a multi-position switch, means to position said switch under the joint control of said primary
- registering devices, a secondary registering device comprising a plurality of relays arranged on a coordinate basis, energizing circuits for said relays, means to successively prepare circuits for the relays with respect to their grouping as regards a primary ordinate, and means to selectively complete said energizing circuits with respect to their grouping as regards a secondary ordinate in accordance with the position assumed by said switch, and means to selectively operate said automatic switches under the control of said secondary registering devices.
15. In a telephone exchange system, subscribers' lines, automatic switches to be used in establishing interconnections between said lines, a plurality of primary registering devices, a multi-position switch including a movable brush set and a contact bank served thereby, means to position said switch under the joint control of said primary registering devices, a secondary registering device comprising a plurality of groups of relays, means to selectively complete circuits for desired ones of said relays, said circuits being controlled at brushes of said multi-position switch, means to complete locking circuits for said relays, and means to selectively operate said automatic switches under the control of said secondary registering devices.
16. In a telephone exchange system, subscribers' lines, automatic switches to be used in establishing interconnections between said lines, a plurality of primary registering devices, means to selectively position said primary registering devices, a multi-position switch including a movable brush set and a contact bank served thereby, means to position said switch under the joint control of said primary registering devices, a secondary registering device comprising a plurality of groups of relays there being an equal number of relays in each of said groups, energizing circuits for said relays, means controlled at the brushes of said multi-position switch to simultaneously prepare the energizing circuits of a set of corresponding relays in all groups, means to selectively complete circuits for desired ones of said corresponding relays, means to complete locking circuits for said relays, and means to selectively operate said automatic switches under the control of said secondary registering devices.
17. In a telephone exchange system, subscribers' lines, automatic switches to be used in establishing connections between said lines, a plurality of primary registering devices, means to selectively position said primary registering devices, a multi-position switch including a movable brush set and a contact bank served thereby, means to position said switch under the joint control of

- 5 said primary registering devices, a secondary registering device comprising a plurality of relays, an impulse generating device for selectively completing circuits of 5 desired ones of said relays, said circuits being controlled at the brushes and contacts of said switch, and means to selectively operate said automatic switches under the control of said secondary registering devices.
- 10 18. In a telephone exchange system, a plurality of registering devices, means to selectively position said registering devices, a multi-position switch, a contact bank served by said switch and divided into groups 15 and subgroups, and means to operate said switch in successive hunting movements to accomplish group, subgroup and contact selection under the joint control of said registering devices.
- 15 19. In a telephone exchange system, a plurality of registering devices, means to selectively position said registering devices, a multi-position switch, a contact bank served by said switch and divided into groups 20 and subgroups, and means to operate said switch in three successive hunting movements to accomplish group, subgroup and contact selection under the joint control of said registering devices.
- 25 20. In a telephone exchange system, a plurality of registering devices, means to selectively position said registering devices, a multi-position switch, a contact bank served by said switch, and means to operate said switch in either two or three successive hunting movements to accomplish the selection of a desired contact under the joint control of said registering devices.
- 30 21. In a telephone exchange, a plurality 40 of registering devices, means to selectively position said registering devices, a multi-position switch, a contact bank served thereby, means to operate said switch in either two or three successive hunting movements 45 to accomplish the selection of a desired contact under the joint control of said registering devices, and means to determine whether the switch shall be moved in two or three hunting movements, said last means 50 being under the control of one of said registering devices.
- 55 22. In a telephone exchange system, a variably operable key set, a multi-position switch, a contact bank served by said switch, and divided into groups and subgroups, and means to operate said switch in three successive hunting movements, to accomplish group, subgroup and contact selection under the control of said key set.
- 60 23. In a telephone exchange system, a variably operable key set, two groups of keys, a multi-position switch, a contact bank served thereby, and means to operate said switch in either two or three successive hunting 65 movements under the control of said keys.
24. In a telephone exchange system, two groups of keys, a multi-position switch, a contact bank served thereby, means to actuate said switch in either two or three successive hunting movements to accomplish the selection of a desired contact set under the joint control of said keys, and means associated with one of said groups of keys to determine whether the switch shall be moved in two or three hunting movements. 75
25. In a telephone exchange system, a plurality of registering devices, means to selectively position said registering devices, a multi-position switch, a contact bank served by said switch, an auxiliary switch 80 associated with said multi-position switch, means to operate said multi-position switch in either two or three successive hunting movements to accomplish the selection of a desired contact set under the joint control of said registering devices, and means including said auxiliary switch to determine whether two or three successive hunting movements shall take place, said auxiliary switch being for this purpose under the control of one of said registering devices. 85
26. In a telephone exchange system, subscribers' lines, automatic switches to be used in establishing inter-connections between said lines, a plurality of sets of primary registering devices, means to selectively position a desired one of said sets of primary registering devices, a plurality of multi-position switches, there being one of said switches individual to each set of primary registering devices, a multiple contact bank served by said switches, means to position an associated switch under the joint control of said actuated set of primary registering devices, a set of secondary registering devices individual to each of said switches, means common to said multi-position switches and controlled in accordance with the position assumed by said actuated switch for setting said secondary registering devices, 100 and means to selectively operate said automatic switches under the control of said secondary registering devices. 105
27. In a telephone exchange system, subscribers' lines, automatic switches to be used in establishing inter-connections between said lines, a plurality of sets of primary registering devices, means to selectively position a desired one of said sets of primary registering devices, a multi-position switch 110 individual to each set of primary registering devices, a multiple contact bank served by said switches, means to position an associated switch under the joint control of said actuated set of primary registering devices, a set of secondary registering devices individual to each of said switches, an electrical device common to said switches and variably connected to the contact sets in said contact bank for controlling the setting of 115

said secondary registering devices, and means to selectively operate said automatic switches under the control of said secondary registering devices.

5 28. In a telephone system, a plurality of primary registers, a secondary register, cross connecting means comprising an impulser therebetween, a selective switch, and means comprising said secondary register and said 10 cross connecting means and jointly controlled by said primary registers for controlling said switch.

15 29. In a telephone system, a primary register, a secondary register, cross connecting means comprising an impulser therebetween, and a selective switch controlled thereby.

20 30. In a telephone system, primary and secondary registers, an impulser therebetween, and a selective switch controlled thereby.

25 31. A telephone system comprising a primary register, a translator therefor, a secondary register, a selective switch controlled thereby, and a cross connecting switch bank between said translator and said secondary register.

32. In a telephone system, a plurality of senders, each including a register switch, a cross connecting frame, multiple contacts for said register switch extending to said cross 30 connecting frame and means to vary the effect of a given corresponding setting of said register switches on all senders by changing a single connection at said cross connecting frame.

35 33. The method of facilitating changing the routing of a call in a system wherein a plurality of registers governing automatic switch controlling devices which in turn direct automatic switches are employed, which 40 consists in changing the relation of one of said registers with respect to said switch controlling devices and thereby similarly changing the relation of the other registers with respect to said switch controlling 45 devices.

In witness whereof, I hereunto subscribe my name this 8 day of June A. D. 1920.

ALBEN E. LUNDELL.

In witness whereof, I hereunto subscribe my name this 28th day of June A. D. 1920.

JAMES J. WYNNE.
